Philip A. Fenell
ATTORNEY.

UNITED STATES PATENT OFFICE.

RUDOLPH KITZBERGER, OF OMAHA, NEBRASKA.

WINDOW.

Application filed May 16, 1923. Serial No. 29,984.

The invention relates to windows and has for its object to provide a device of this kind wherein the sash may be placed in the window frame on the inside thereof and easily removed from the inside of the window frame for cleaning or repair purposes.

A further object is to provide the window frame with a plurality of pairs of sash and a pair of screens thereby forming an absolutely dust proof window adapted for building or car purposes, and at the same time the use of parting strips within the frame obviated, and the sash provided with lugs extending into grooves in the sides of the window frame for forming pivotal points for the sash as well as guiding means during the raising and lowering of the sash.

A further object is to provide spaced vertically disposed channels in the sides of the window frame adjacent the pairs of sash for the reception of the lugs carried by the sash, a connecting channel between the grooves, said grooves forming means whereby either sash may be raised or lowered as desired.

25 A further object is to provide the frame with metallic strips angularly shaped in cross section, one flange of which is received in grooves in the outer sides of the sash for forming a dust and weather proof joint.

30 A further object is to provide the lower ends of the sash with fixed pins extending to the channel for forming pivotal points for the sash and the upper end of the sash with retractable pins, which when retracted allow 35 the sash to swing inwardly to horizontal positions when it is desired to repair or clean the outer sides of the sash.

With the above and other objects in view the invention resides in the combination and 40 arrangement of parts as hereinafter set forth, shown in the drawing, described and claimed, it being understood that changes in the precise embodiment of the invention may be made within the scope of what is 45 claimed without departing from the spirit of the invention.

In the drawing:—

Figure 1 is a perspective view of the window frame.

50 Figure 2 is a vertical transverse sectional view through the window frame and sash.

Figure 3 is a horizontal sectional view taken on line 3—3 of Figure 1.

55 Figure 4 is a sectional view taken on line 4—4 of Figure 1.

Figure 5 is a vertical transverse sectional view taken on line 5—5 of Figure 1.

Figure 6 is a perspective view of one of the upper pivot bolts of the sash.

Figure 7 is a perspective view of one of the storm bolts.

Referring to the drawing the numeral 1 designates the window frame, the sides 2 of which are provided with shoulders 3 and 4, and against the shoulders 3 weatherstrips 5 are disposed, which weatherstrips are right angularly shaped in cross section, and have one of their flanges disposed in channels 6 in the outer faces of the window sash 7 for forming a dust proof connection. It will be noted that the shoulders 3 and 4 are in staggered relation therefore it will be seen that the sash 7 may be easily placed in the frame 1 or removed therefrom from the inner side of the frame, thereby allowing the sash to be easily removed for reputting or cleaning purposes. The shoulders 3 and 4 extend across the upper end of the frame as well as the strips 5, therefore it will be seen that a dust and weather proof connection is formed along the vertical sides of the sash and also along the upper end of the upper sash. The screen 8 is formed preferably in two sections as clearly shown in Figure 2 and rest against the shoulders 4 of the frame, therefore it will be seen that the screen may be easily removed from the frame inwardly therethrough, thereby obviating the difficulty of placing screens in position, at present experienced, especially with full length screens. The adjacent ends of the sash 7 overlap as clearly shown in Figure 2, and are provided with angular weather stripping 9, similar in construction and operation as the strip 5.

The lower ends of the sash 7 have secured thereto plates 10, which plates are provided with lugs 11, which extend into the vertically disposed grooves 12 and guide the sash in its upward movement, and at the same time upon inward pivotal movement of the sash form pivotal points therefor. The grooves 12 are disposed in the sides of the frame 1 in a position where they are substantially concealed by sash when in normal position as shown in Figure 2. The upper ends of the grooves 12 terminate in upwardly and inwardly inclined grooves 13, which in turn terminate in horizontally disposed grooves 14, in which grooves the retractable

lugs 15, carried by the plates 16, at the upper ends of the sash, are disposed, that is of the upper sash. When it is desired to lower the upper sash 7 after the lower sash has 5 been moved inwardly, the upper sash is pulled inwardly at its upper end, which will move the retractable lug 15 to a position where they will be received in the inclined grooves 13, and the sash out of engagement 10 with the upper portion of the weather strip 5, after which the sash can be moved downwardly, guided by the lugs 15 and the lugs 11 in the groove 12. Frame 1 is provided with grooves 16 inwardly spaced from 15 the grooves 12 and in parallel relation therewith. The lower ends of the grooves 16 incline downwardly and outwardly at 17 and are connected to the lower end of the grooves 12. They are also connected to the grooves 20 12 adjacent the upper end of the lower sash by means of horizontally disposed grooves 18, therefore it will be seen that the lower sash may be pulled inwardly at its upper end for forcing the retractable lugs 15 through the 25 grooves 18 into the grooves 16 and then the lower sash can be raised, and the lugs 15 and 11 thereof forced upwardly into the grooves 16. When it is desired to swing the sash inwardly for repairing or cleaning the outer 30 sides thereof, it will only be necessary for the operator to retract the retractable lugs 15 at the upper ends of the sash, which will allow said sash to swing inwardly on the lugs 11 as pivotal points, and the sash may be 35 placed in a horizontal point or at any other angle. The opposite sides of the sash 7 are preferably provided with storm bolts 19 which additionally hold the sash against movement and in position. However to further hold the sash and lock the same together 40 a conventional form of pivoted ring controlled latching device is provided on the

lower sash which cooperates with the upper sash as clearly shown in Figure 5.

From the above it will be seen that a window frame and sash is provided which is simple in construction, positive in its operation and constructed in a manner whereby the sash will not only form a dust proof window, but one wherein all of the sash can 45 be easily and quickly removed from the inside of the frame, or the sash placed in position where the outer sides thereof may be easily repaired or cleaned.

The invention having been set forth what 55 is claimed as new and useful is:—

A sash mounting for window frames comprising vertically disposed parallel grooves in the inner faces of a window frame, guide lugs carried by the sash adjacent their upper and lower ends, the upper guide lugs being retractable, the lower ends of said grooves being connected together by means of downwardly and outwardly inclining grooves, connecting horizontal grooves between the vertically disposed grooves adjacent the upper guide lugs of the lower sash and inwardly, upwardly and outwardly inclined grooves carried by the upper ends of the outer vertical grooves adjacent the 60 upper guide lugs, said upper guide lugs being retractable vertically disposed and inwardly extending strips carried by the window frame and disposed in channels in the outer faces of the sash, horizontally disposed 65 inwardly extending flanges carried by the upper side of the frame and the lower end of the upper sash and disposed in horizontally disposed channels in the adjacent sash ends, said flanges forming weather strips 70 and locking means for the sash.

In testimony whereof I hereunto affix my signature.

RUDOLPH KITZBERGER.
